(57) **CLAIM**

The ornamental design for a watch dial, as shown and described.

DESCRIPTION

FIG. 1 is a front, top perspective view of a first embodiment of a watch dial showing my present invention in a first state of a first sequence.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a front, top perspective view thereof in a second state of the first sequence.

FIG. 9 is a front, top perspective view thereof in a third state of the first sequence.

FIG. 10 is a front, top perspective view thereof in a fourth state of the first sequence.

FIG. 11 is a front, top perspective view thereof in a fifth state of the first sequence.

FIG. 12 is a front, top perspective view thereof shown in sixth state of the first sequence.

FIG. 13 is a front, top perspective view thereof shown in a seventh state of the first sequence.

FIG. 14 is a front, top perspective view of a second embodiment of the watch dial.

FIG. 15 is a top plan view thereof.

FIG. 16 is a rear plan view thereof.

FIG. 17 is a front elevation view thereof.

FIG. 18 is a rear elevation view thereof.

FIG. 19 is a right side elevation view thereof.

FIG. 20 is a left side elevation view thereof.

FIG. 21 is a front, top perspective view of a third embodiment of the watch dial, shown in a first state of a second sequence.

FIG. 22 is a front, top perspective view thereof shown in a second state of the second sequence.

FIG. 23 is a front, top perspective view thereof shown in a third state of the second sequence.

FIG. 24 is a front, top perspective view thereof shown in a fourth state of the second sequence.

FIG. 25 is a front, top perspective view thereof shown in a fifth state of the second sequence; and,

FIG. 26 is a front, top perspective view thereof shown in a sixth state of the second sequence.

The appearance of the watch dial sequentially transitions between the states shown in FIGS. 1 and 8-13, and between FIGS. 21-26, respectively. The process or period in which one state transitions to another state forms no part of the claimed design. The dash-dash lines show environmental
